(57) **CLAIM**

The ornamental design for an entertainment center, substantially as shown and described.

DESCRIPTION

FIG. 1 is a perspective view of the entertainment center; FIG. 2 is a front view thereof, including phantom views of a vertically mounted AV component and a horizontally disposed AV component; and,

FIG. 3 is a first side view thereof, including phantom views of a vertically mounted AV component and a horizontally disposed AV component;

FIG. 4 is a second side view thereof; and,

FIG. 5 is a top view thereof.

The broken lines are for illustrative purposes only and form no part of the claimed design.
